CLAIM

The ornamental design for a urine container body as shown and described.

DESCRIPTION

FIG. 1 is a front view of a urine container body in accordance with aspects of the present subject matter.

FIG. 2 is a top view of the urine container body illustrated in FIG. 1.

FIG. 3 is a first or right side view of the urine container body illustrated in FIG. 1.

FIG. 4 is a second or left side view of the urine container body illustrated in FIG. 1.

FIG. 5 is a perspective view of the urine container body illustrated in FIG. 1.

FIG. 6 is another perspective view of the urine container body illustrated in FIG. 1.

FIG. 7 is a front view of the urine container body illustrated in FIG. 1, shown in a position of use; and,

FIG. 8 is another front view of the urine container body illustrated in FIG. 1, shown in a position of use.

Contour lines and/or surface shading, to the extent applicable, are illustrated simply for purposes of highlighting the solid-rendering, and, thus, form no part of the claimed design. Additionally, the images of the person using the urine container body are shown simply for purposes of illustrating the environment, and, thus, form no part of the claimed design.
